UNITED STATES PATENT OFFICE.

LORENZO STOWE, OF JACKSON, TENNESSEE.

BACK-BAND HOOK.

SPECIFICATION forming part of Letters Patent No. 684,879, dated October 22, 1901.

Application filed March 6, 1901. Serial No. 50,113. (No model.)

To all whom it may concern:

Be it known that I, LORENZO STOWE, a citizen of the United States, residing at Jackson, in the county of Madison and State of Tennessee, have invented certain new and useful Improvements in Back-Band Hooks; and I do hereby declare the following to be a full, clear, and exact description of the invention, such as will enable others skilled in the art to which it appertains to make and use the same.

This invention aims to provide a back-band hook that will not injure or distress the animal; that will be light, durable, and strong; that will adapt itself to thick or thin web without cutting, punching, or otherwise injuring it, and that will securely hold the trace-chain and yet admit of it being quickly attached to and removed from the hook and which will be free from projecting parts which would tend to catch into any part of the harness.

For a full description of the invention and the merits thereof and also to acquire a knowledge of the details of construction of the means for effecting the result reference is to be had to the following description and drawings hereto attached.

While the essential and characteristic features of the invention are necessarily susceptible of modification, still the preferred embodiment of the invention is illustrated in the accompanying drawings, in which—

Figure 1 is a front view of a back-band hook or buckle embodying the invention. Fig. 2 is an end view thereof. Fig. 3 is a vertical section about on the line X-X of Fig. 1, the back-band being in position. Fig. 4 is a perspective view, the mousing being open.

Corresponding and like parts are referred to in the following description and indicated in all the views of the drawings by the same reference characters.

The frame of the buckle comprises a plate 1, having a hook 2 at its lower edge and bent end portions. This plate is formed with a longitudinal slot 3, terminating a short distance from the bent ends and adapted to receive the fold 4 of the web 5. One of the bent ends of the plate or frame is provided with a vertical slot 6, into which an end of the mousing 7 is looped, and the other bent end is formed with an approximately L-shaped

slot 8 and an opening 9. The web-holder 10 is loosely connected at one end with the frame of the buckle by having an end portion passed through the opening 9 and formed into an eye. The hook 2 is centrally disposed, so as to equalize the load and strain upon the web 5.

The mousing 7 consists of a half-round bar having a tongue 11 at one end, which is passed through the slot 6 and bent into a roll or knuckle, so as to form pivotal connection between the mousing and the frame of the buckle. A notch 12 is formed at the opposite end of the half-round bar to receive the end portion of the holder 10, looped into the opening 9. A slit 13 extends inward a short distance from the free end of the mousing or pivoted bar, and the portion 14, separated from the body of the bar by the slit 13, constitutes a spring-catch, the free end of which is adapted to pass into the L-shaped slot 8 and hold the mousing when closed over the fold 4 and web-holder 10. The catch 14 springs outward, so as to enter the return portion of the slot 8 and hold the mousing when closed. A tongue 15 is provided centrally of the bar or mousing and co-operates with the hook 2 to prevent disengagement of the trace-chain when engaged with the said hook.

The web-holder 10 is of spiral formation and is formed of a length of stout wire coiled throughout its length, the coils being of slightly larger diameter than the width of the slot 3, so as to prevent the withdrawal of the part 10 through said slot when the web 5 is under tension. The volutes, spirals, or coils of the web-holder 10 serve to engage forcibly with the folded portion 4 of the web and prevent slipping thereof or the buckle 90 when the latter is adjusted and properly fastened by drawing the fold 4 tight about the web-holder 10 and through the slot 3. After the buckle has been adjusted on the web the fold 4 and the web-holder are protected and hidden from view by the mousing, which extends thereover, said parts entering the space formed in the concave or hollow side of the bar comprising the mousing.

The buckle-frame and mousing may be cast, pressed, or struck up from sheet metal, the construction being such as to admit of the frame and mousing being stamped from sheet metal of proper gage. The bent end portion

of the frame having the slot 8 and opening 9 has the upper part constructed to enter the outer end of the mousing or half-round bar and close the same, thereby preventing any 5 vertical movement of the mousing when closed.

Having thus described the invention, what is claimed as new is—

1. In a back-band buckle, and in combination with the frame having a longitudinal slot, a web-holder of spiral formation adapted to fit in the fold of the web and connect the same to the frame of the buckle, substantially as set forth.
- 15 2. In a back-band buckle, and in combination with the frame having a longitudinal slot, a web-holder of spiral formation having loose or pivotal connection at one end with an end portion of the buckle-frame and adapted to enter the fold of the web, substantially as set forth.
- 20 3. In a back-band buckle, and in combination with the frame having a bent end portion, a half-round bar having pivotal connection at one end with an end of the frame and having an integral catch at the opposite end formed by slitting the bar a short distance from its free end, said catch coöperating with a slot of the aforementioned bent end of the

frame to hold the mousing closed, substantially as set forth. 30

4. In a back-band buckle, a frame having bent end portions, a mousing comprising a half-round bar having pivotal connection at one end with the bent end of the frame, and having an integral catch at its opposite end for coöperation with the other bent end of the frame to hold the mousing closed, and a web-holder inclosed by the said mousing, substantially as set forth. 35

40 5. In a back-band buckle, a frame having a longitudinal slot and a bent end portion, the latter having an approximately L-shaped slot, a web-holder loosely connected with the bent end of the frame, and a mousing having its free end portion formed with a notch and an integral catch, the notch clearing the pivotal end of the web-holder, and a portion of the bent end of the frame entering and closing the outer end of the mousing, substantially as and for the purpose set forth. 45

50 In testimony whereof I affix my signature in presence of two witnesses.
